Patented Jan. 31, 1922.

C. E. Edge

By William C. Linton.

Attorney

UNITED STATES PATENT OFFICE.

CHARLES ERNEST EDGE, OF ROCKY MOUNT, NORTH CAROLINA.

PROTECTIVE DEVICE.

1,405,106.

Specification of Letters Patent.

Patented Jan. 31, 1922.

Application filed October 15, 1921. Serial No. 508,032.

To all whom it may concern:

Be it known that I, CHARLES E. EDGE, a citizen of the United States, residing at Rocky Mount, in the county of Edgecombe and State of North Carolina, have invented certain new and useful Improvements in Protective Devices; and I do hereby declare that the following is a full, clear, concise, and exact description of the same, such as will enable others skilled in the art to which it appertains to make and use the same.

This invention relates to improvements in dentists' accessories, having for an object to provide a protective device for preventing the inter inhalation of breath as between a dentist and patient, whereby to avoid disagreeable conditions, at times occasioned thereby, and also, to protect either or both the dentist and patient from infection or diseases, often times resulting therefrom as for illustration, the prevention of passage of tubercular germs from one of the persons to the other.

It is also an object of the invention to provide a device of the character mentioned which can have the intake nozzle thereof adjusted to various positions whereat it will effectually function, and yet, will not be troublesome to or hinder the dentist in his work upon a patient.

Other objects will be in part obvious and in part pointed out hereinafter.

In order that the invention and its mode of operation may be readily understood by persons skilled in the art, I have in the accompanying illustrative drawings and in the detailed following description based thereon set out one possible embodiment of the same.

40 In these drawings:

Figure 1 is a perspective view of the invention; and,

Figure 2 is a vertical section through the cabinet.

45 Having more particular reference to the drawings, in connection with which like characters of reference will designate corresponding parts throughout, my improved device consists of an ornamental form of cabinet 1 which may be constructed of wood, metal, or various other material such as conditions or preference may dictate and finished or otherwise decorated as may be desired. An opening 2 is formed in one side 50 of the cabinet and is adapted to be closed

by a horizontally swingable door 3 having a latch 4 thereon adapted to engage with a suitable form of keeper adjacent one side of said doorway 2. Thus, it will be understood that access may be had to the interior 60 of the cabinet 1 and if desired, a plurality of superposed shelves 5 may be arranged within the same for receiving various articles. Casters or rollers 6 may be and preferably are arranged upon the various corner 65 portions of the lower end of the cabinet 1 and serve for an obvious purpose.

Extending through and arranged vertically within the cabinet 1 is a conduit 7 having its upper end extended for a distance 70 above the top of the cabinet 1 and fitted with an elbow connection 8, while the lower end of the same is correspondingly fitted and receives thereon the inner end of a flexible conduit 9, which as will be noted, passes 75 through a recess provided therefor in the adjacent portion of the side wall of the cabinet, from whence it is extended into connection with such fan or an air pump 10, 80 said pump, being preferably arranged in the laboratory of a user or at a point whereat it will be inconspicuous. In this connection, it is to be noted that a bag or other receptacle 11 is interposed as between the conduit 9 and the pump 10 and by consequence, 85 matter passing through the conduit under influence of the suction created therein by the pump 10 will be deposited in the bag. Of course, the bag is removable in order that it may be emptied or replaced by a clean 90 bag as may become necessary.

Rotatably connected to the free portion of the elbow 8 is a corresponding or substantially right angular fitting 12 having the free end thereof formed to rotatably receive an extension conduit 13, the outer end of which carries another elbow fitting 14, which as will be noted, has rotatable connection with the same. This fitting 14 carries a nozzle 15 upon its outer end which is adapted, by reason of the suction created there-through, to prevent the inter inhalation of breath as between the dentist or a patient, the inhalation of globules of moisture by the dentist coming from the mouth of a patient 105 being treated, the filing of a tooth being ground, and various other matters.

By reason of the mounting of the nozzle 15, it will be understood that the same may be moved to various positions, since the ar- 110

rangement of the elbows 12 and 14 and the conduit extension 13 is such as to permit of compound movement as between the same. Thus, the nozzle may be adjusted by the dentist to various positions whereat it will effectually serve for its purpose and yet, will not become troublesome to or hinder him in his work upon a patient.

It is to be also understood that the improved device may be successfully used for removing soiled pieces of absorbent cotton and like matter, as removed from the mouth of a patient by the dentist, thus eliminating the usual unsanitary practice of dropping such matter into a waste receptacle, which often times, is open and will permit of the spreading of such germs as may be collected by the same, when dried. Also, due to the fact that the nozzle 15 is placed in a position 20 in proximity to the dentist and patient, it will be understood that the dentist may readily place a piece of soiled absorbent cotton before the nozzle 15 without interrupting his work upon a patient, such as is occasioned by the placing of such pieces of absorbent cotton in a waste receptacle to one side of the operating shaft.

In order that the energization of the motor 10 may be conveniently controlled by 30 a user of the device, an electrical switch 16 may be and preferably is arranged upon one side wall of the cabinet 1 and is connected to one side of the electrical circuit supplying energy to said motor. Thus, by 35 actuating the switch, the motor may be either stopped or started.

Manifestly, the construction shown is capable of considerable modification and such modification as is within the scope of my 40 claims, I consider within the spirit of my invention.

I claim:

1. A device of the character described comprising a conduit adapted to have a suction created through one end of the same, 45 an elbow fitting rotatably engaged with said end of the conduit, an extension conduit rotatably engaging the free end of said elbow fitting, a second elbow fitting rotatably engaging the free end of said conduit, and a 50 nozzle secured to the free end of said second fitting.

2. A device of the character described, comprising a cabinet, a vertical conduit within said cabinet adapted to have a suction 55 created through the upper end of the same, and a nozzle secured to said upper end of the conduit mounted for horizontal and vertical adjustment with relation to the same.

3. A protective device of the character described comprising a portable support, a conduit carried by said support and adapted to have a suction created through one end thereof, an intake nozzle adjustably mounted upon said end of the conduit and said 60 nozzle being arranged about said support substantially as and in the manner specified.

4. A protective device of the character described comprising in combination a portable cabinet, a conduit arranged within and 70 extending through said cabinet, an extension communicating with and secured to the upper end of said conduit, an intake nozzle adjustably connected to the upper end of said extension, and a flexible conduit adapted to 75 have a suction created therein and said flexible conduit being in communication with the lower end of the conduit arranged within said cabinet.

In witness whereof I have hereunto set 80 my hand.

CHARLES ERNEST EDGE.
